DESIGN FOR A SPORT HAT

Helene S. Jaccard, Mission Hills, Kans.

Application July 21, 1938, Serial No. 78,637

Term of patent 14 years

To all whom it may concern:

Be it known that I, Helene S. Jaccard, a citizen of the United States, residing at 1502 Drury Lane, Mission Hills, in the county of Johnson and State of Kansas, have invented a new, original, and ornamental Design for a Sport Hat, of which the following is a specification, reference being had to the accompanying drawing, forming part thereof.

In the drawing:

Fig. 1 is a perspective view of the sport hat showing my new design.

Fig. 2 is a side elevation of the hat, shown in Fig. 1.

Fig. 3 is a rear elevation thereof.

I claim:

The ornamental design for a sport hat, as shown.

HELENE S. JACCARD.
